UNITED STATES PATENT OFFICE.

EDGAR C. CHANDLER, OF PHILADELPHIA, PENNSYLVANIA.

PATTERN DEVICE FOR KNITTING-MACHINES.

977,852.

Specification of Letters Patent.

Patented Dec. 6, 1910.

Original application filed August 18, 1908, Serial No. 449,181. Divided and this application filed September 14, 1909. Serial No. 517,562.

To all whom it may concern:

Be it known that I, EDGAR C. CHANDLER, a citizen of the United States, residing at the city and county of Philadelphia, State 5 of Pennsylvania, have invented certain new and useful Improvements in Pattern Devices for Knitting-Machines, of which the following is a specification.

This application is a division of my application for my Letters Patent No. 953,122, dated March 29, 1910, for an improvement in knitting machines.

The object of this invention is to provide in a knitting machine a simple and efficient 15 construction and organization of parts whereby various different patterning effects may be produced in the product of the machine, by causing, at predetermined intervals, certain of the needles to produce 20 "tuck" stitches while the remaining needles produce the regular stitches, and by causing the needles to cease the production of the "tuck" stitches at predetermined intervals.

The invention consists in the novel construction and combinations of parts which 25 will be hereinafter fully described and claimed.

In the drawings:—Figure 1 is a plan view of a knitting machine embodying my invention. Fig. 2 is a side elevation thereof. Fig. 3 is a longitudinal section, as on the line *a—a* of Fig. 1. Fig. 4 is a section on line *b—b* of Fig. 1. Fig. 5 is a section on line *c—c* of Fig. 1. Fig. 6 is a section on line *d—d* of Fig. 1. Fig. 7 is a view of the pawl-raising arm, detached. Fig. 8 is a section on line *e—e* of Fig. 1. Fig. 9 is a section on line *f—f* of Fig. 1. Fig. 10 is a section on line *g—g* of Fig. 1. Fig. 11 is a 30 development of a portion of the interior of the cam cylinder showing the two sets of knitting cams, one of the adjustable needle-raising cams and one of the needle-operating wheels. Fig. 12 is a horizontal section as 35 on the line *h—h* of Fig. 2.

The main frame of the machine comprises a bedplate 1, and a suitable supporting standard 2 therefor. Mounted in suitable bearings in the standard 2 is the main driving shaft 3, the outer end of which is provided with the usual fast and loose pulleys 4 and 5, by means of which power may be applied to the shaft. The inner end of the shaft 3 is provided with a beveled gear

wheel 6 which engages the teeth of a similar gear wheel 7 formed on the cam cylinder 8 which is rotatably mounted in the bed plate 1. Within the cam cylinder 8 is the needle cylinder 9 provided with the usual vertical grooves into which are fitted the needles 10 of usual construction. The cam cylinder 8 carries the usual cams for vertically reciprocating the needles for the production of the stitches in the common and well known manner. In the present invention two sets 55 of knitting cams of usual construction are carried by the cam cylinder and on opposite sides thereof, as at A and B, whereby, during the rotation of the cam cylinder 8 the needles will be actuated to produce two rows 60 of stitches for every revolution of the cam cylinder.

The construction and operation of the knitting cams for the production of the 65 stitches are common and well known and no detailed description or illustration thereof is deemed necessary herein.

Rising from the cam cylinder 8 on opposite sides thereof, are posts 18 and 19 between which extends a frame 20 in which 70 is formed a ring 21 which surrounds the needles 10 and forms the usual guard for the latches thereof. This ring 21 is provided with a thread-guiding eye 22 through which a thread is directed to the needles adjacent the knitting cams B; and the ring 21 carries an arm 24 provided with a thread-guiding eye 25 through which a thread is directed to the needles adjacent the knitting 75 cams A.

In carrying out my invention, I employ an automatically controlled mechanism to raise certain of the needles so that their latches will escape their engaged loops of thread while the latches of other needles are permitted to remain in their engaged 80 loops of thread to produce "tuck" stitches during the knitting operation, to control the pattern effect of the fabric being knitted.

Directly in rear of the knitting cams B 85 is a needle-operating wheel 54 which inclines upwardly in a direction away from the knitting cams, and directly in rear of the knitting cams A is a needle-operating wheel 55 which inclines upwardly in a direction 90 away from the knitting cams. The wheels 54 and 55 are mounted to rotate on pivot studs 56 and 57 respectively, carried 95 100 105

by the cam cylinder 8. The edge of each wheel is provided with suitable notches adapted to engage the butts of certain predetermined needles and raise them so that 5 their latches will escape their engaged loops of thread after they have been acted upon by the preceding knitting cams, and each wheel is also provided with slots between the notches for the passage therethrough of the butts of the needles not raised by the 10 wheel. The latches of the needles not raised by the wheels 54 and 55 are thus permitted to remain in their engaged loops of thread, thus causing certain needles to "tuck" during 15 the knitting operation and produce pattern effects upon the fabric being knitted.

Directly in rear of each wheel 54 and 55 is a pattern-controlling, needle-operating cam 58, which is formed on the inner end of 20 a radially extending bar 59. The bar 59 is pivotally mounted, as at 60, on a bracket 61 projecting from and carried by the cam cylinder 8. The bars 59 are adapted to be rocked on their pivots by mechanism hereinafter described, to raise and lower the 25 cams 58, and the cams 58 are held in either their raised or lowered position by the action of a flat spring 62 secured to the brackets 16 and engaging V-shaped lateral faces 30 of the cams 58. When the cams 58 are in the lowered position, the butts of the needles are unaffected thereby. When, however, the cams 58 are in the raised position, they act upon the butts of the needles not acted upon 35 by the notches of the preceding wheels 54 and 55 and raise said needles so that their latches escape their engaged loops of thread. Thus it will be seen that when the cams 58 are in the raised position, all of the needles, 40 after they have been acted upon by the knitting cams A and B will be raised so that their latches will escape their engaged loops of thread, and that therefore no tucking will take place; and that when the cams 45 58 are in the lowered position, the needle butts will be unaffected thereby and certain needles controlled by the wheels 54 and 55 will be caused to tuck as previously explained. Thus the raising and lowering of 50 the cams will control the tucking operation; or, in other words, when the cams 58 are in the raised position, no tucking will take place, and when the cams are in the lowered position the tucking operation will take 55 place.

The notches 54 and 55 may be arranged to engage any predetermined needles to control the pattern effect of the tucking stitches in the product of the machine, and either 60 one or both of the wheels 54 and 55 may be removed from the machine and other wheels having differently arranged notches to engage different needles may be substituted therefor. Thus a great variety of pattern 65 effects, due to the tucked stitches, may be

produced in the knitted fabric by the employment of different wheels having differently arranged needle-engaging notches.

The outer ends of the cam bars 69 are adapted to be engaged by two reciprocative 70 pins 62 and 63, arranged one above the other. These pins are adapted to be projected in alternate succession into the path traversed by the outer ends of the cam bars, and the outer ends of the cam bars are provided with upper and lower beveled surfaces which are adapted to be engaged by the pins 62 and 63 to raise and lower the outer ends of the bars 59, and at the same time raise and lower the cams 58 carried by 80 the inner ends thereof. The pin 62 is so positioned with relation to the path of travel of the outer ends of the bars 59 that when it is projected into the path thereof it will act upon the upper beveled faces of the 85 outer ends of the bars to depress them and raise the cams 58. And the pin 63 is so positioned with relation to the path of travel of the outer ends of the bars 59 that when it is projected into the path thereof it 90 will act upon the lower beveled faces of the outer ends of the bars to raise them and lower the cams 58.

The pins 62 and 63 are fitted to horizontal openings in a bracket 44 rising fixedly 95 from the bed plate 1 and the outer ends of the pins are pivotally connected to the upper and lower ends of a plate or lever 64 which is pivotally connected to the bracket 44 as at 65, centrally between the two pins 62 and 100 63. The central portion of the plate or lever 64 extends outwardly from the bracket 44 and is connected by an upwardly extending link 66 to a horizontally arranged arm 67 which is pivotally mounted on a shaft 51 105 mounted in bearings in a bracket 52 projecting from the bed plate 1. The free end of the arm 67 is drawn downward by the action of a spring 68, one end of which is connected to the arm 67 and the other end 110 of which is connected to the bracket 44.

From this construction it will be seen that when the arm 67 is raised against the action of the spring 68, the link 66 will act upon and rock the plate or lever 64 in a manner to withdraw the pin 63 from the path of the cam bars 59 and project the pin 62 into the path of the cam bars 59; and when the arm 67 is lowered by the action of the spring 68, the link will act upon and rock the plate or lever 64 in a manner to withdraw the pin 62 from the path of the cam bars 59 and project the pin 63 into the path of the cam bars; so that when the pin 63 is projected inwardly the cams 58 will be lowered, permitting the production of the tucked stitches; and when the pin 62 is projected inwardly the cams 58 will be raised to cause the needles to cease the production of the tucked stitches.

By automatic mechanism which I shall now describe the arm 67 is raised and lowered, to thus control the production or non-production of the tucked stitches. Directly beneath the arm 67 are two independently rotatable members which, in the present embodiment of my invention, are two drums 69 and 70. The drum 70 is fixed to a shaft 71 which is mounted in bearings projecting from the bed plate 1, and the arm 69 surrounds and is rotatably mounted upon the drum 70. The drum 69 is only about one half the length of the drum 70, so that a portion of the periphery of the drum 70 will be exposed while the entire periphery of the drum 69 is exposed. The arm 67 is provided with two downwardly extending projections 76 and 77, which are adapted to move into and out of the paths traversed by projecting blocks 78 and 79 carried by the drums 69 and 70 respectively. Thus it will be seen that when the drums 69 and 70 are rotated independently of each other the stitch-tucking mechanism will be controlled by the arm 67 being raised and lowered by the operation of the blocks 78 and 79. The drums 69 and 70 are provided with screw-threaded holes for the reception of screws to secure other blocks to the drums in the paths of the blocks 78 and 79, or for changing the location of these blocks with respect to each other and the drums 69 and 70, so that they will act upon the arm 67 at different times with relation to the movement of the drums.

By employing two independently rotatable members or drums and by independently controlling both the thread-changing mechanism and the stitch-tucking mechanism such as is described and claimed in my Patent No. 953,122, above mentioned by each of said drums, I am enabled to obtain a much wider range of variation in the pattern of the fabric being knitted than if a single drum were employed.

I shall now describe the mechanism for actuating the drums independently of each other at certain intervals during the operation of the machine.

Formed on or secured to one end of the inner drum 70 is a ratchet wheel 80, and formed on or secured to one end of the outer drum adjacent the ratchet wheel 80 is a ratchet wheel 81. The teeth of the ratchet wheel 80 are directed opposite to the teeth of the ratchet wheel 81 so that they and the drums may be rotated in opposite directions. Engaged with the ratchet wheels 80 and 81 are pawls 82 and 83 respectively, the pawls 82 and 83 being carried by the upper end of a lever 84 fulcrumed on the shaft 71. The lower end of the lever 84 is connected by an arm 85 to a wheel 86 away from the center thereof, whereby, during the rotation of the wheel 86, the lever 89

will be rocked back and forth. The wheel 86 is carried by a shaft 87 having its bearings in the main frame, and the shaft 87 is actuated from the main shaft 3 by the interposed gear wheel 88 and pinion 89. Thus, during the operation of the machine, the lever 84 will be rocked back and forth. The movement of the upper end of the lever 84 in one direction will cause the pawl 83 to engage a tooth of the ratchet wheel 81 and advance the drum 69 the distance of one tooth, and the movement of the upper end of the lever 84 in the reverse direction will cause the pawl 82 to engage a tooth of the ratchet wheel 80 and advance the drum 70 the distance of one tooth in an opposite direction to the movement of the drum 69.

In order to disengage the pawl 82 from the ratchet wheel 80 so that it will discontinue to advance the drum 70 at certain predetermined intervals, for a purpose herein-after explained, I provide an arm 90, one end of which is pivotally mounted on a bracket 91 on the bed plate 1, and the other end of which extends to a position directly beneath the path of movement of the pawl 82, so that when the arm 90 is raised the nose of the pawl 82 will ride over the arm and be prevented from engaging the teeth of the ratchet wheel 80, and when the arm 90 is lowered the pawl 82 will be permitted to drop into engagement with said teeth. The arm 90 is raised at certain intervals by pins 92 which project from a circular series of screw-threaded holes 93 in the face of the ratchet wheel 80 into which the pins 92 are screwed. The timing of the disengagement of the pawl 82 from the ratchet wheel 80 with relation to its movement may be controlled and regulated by employing a greater or less number of pins 92 and by changing their positions about the circular series of openings 93. After the arm 90 has been raised by one of the pins 92, it is held in the raised position by a latch arm 94 provided with a shoulder 95 adapted to engage a lateral projection 96 on the arm 90. The lower end of the latch arm 94 is fixed to a rock shaft 97 which is mounted in bearings in brackets depending from the bed plate 1. The upper end of the arm 94 is drawn normally toward the projection 96 by a spring 98, one end of which is connected to the arm 94 and the other end of which is connected to a projection 99 rising from the arm 90 adjacent the pivot thereof. This spring 98 also tends to move the free end of the arm 90 downwardly from engagement with the pawl 82. As the arm 90 is being raised by a pin 92, the arm does not raise the pawl 82 from the tooth of the wheel 80 with which it is then engaged, but it is raised into position to prevent the pawl dropping into engagement with the next succeeding tooth. This being done, the

spring 98 draws the latch arm 94 into engagement with the projection 96 on the arm 90 to maintain the arm elevated while the pin 92 which raised the arm 90 moves from 5 engagement therewith before the wheel 80 comes to rest, so that the arm 90 may drop from the pawl 82 when the arm 90 is released by the latch arm 94.

When the shoulder 95 is in engagement 10 with the projection 96, and the pawl 82 is out of engagement with the ratchet wheel 80, and it is desired to permit the pawl 82 to drop into engagement with the ratchet wheel 80, the shaft 97 is rocked to disengage the latch arm 94 from the projection 96, thus permitting the arm 90 and pawl 82 to drop. The latch arm 94 is thus operated at certain predetermined intervals by the following mechanism:—One end of the 15 shaft 97 extends outwardly and is provided with an arm 100 the free end of which is provided with a dog 101 arranged directly over a pattern chain 102 which passes over a sprocket wheel 103 on a shaft 104 which 20 is mounted to rotate in a suitable bearing. The lower end of the chain 102 passes around a weighted, grooved wheel 105, which is supported by the chain. The links of the chain, at certain intervals, are provided 25 with projections 106 which, as they pass the free end of the arm 100 during the rotation of the sprocket wheel 103, are adapted to engage the dog 101 and raise the arm 100 in a manner to rock the shaft 97 30 and disengage the latch arm 94 from the pawl-engaging arm 90 and return the pawl 82 into engagement with the sprocket wheel 80. The shaft 104 and therewith the sprocket wheel 103 is continuously and slowly rotated 35 40 by a wheel 107 on the shaft 104, the periphery of the wheel 107 being provided with small comb-like projections which are engaged by the fabric (shown by dot-and-dash lines) which, as it passes from the needles to and between a pair of take-up rollers 108, 45 engages the projections and rotates the wheel 107. The take-up rollers 108 are journaled in a frame 109 one end of which is pivotally mounted on a shaft 110 carried 50 by brackets depending from the bed plate. The shaft 108^a of one take-up roller 108 is provided with a gear wheel 111 which is engaged by a pinion 112 on one end of a shaft 113 journaled in the frame 109. The 55 other end of the shaft 113 is provided with a grooved pulley 114 around which passes a belt 115 which also passes around a grooved pulley 116 on the main driving shaft 3.

During the knitting operation, the fabric 60 is drawn from the needles by the weight of the free end of the frame 109, which is supported by the fabric engaging the take-up rollers 108. As the frame 109 moves downwardly in drawing the fabric from the 65 needles, the frictional engagement of the

belt 115 with the wheel 114 increases until it is sufficient to turn the shaft 113 and therewith the feed rollers 108 in a manner to feed the fabric downwardly between said rollers, thus raising the free end of the frame 109 and decreasing the frictional engagement of the belt 115 with the pulley 114 until it is insufficient to rotate the feed rollers; whereupon the free end of the frame 109 again moves downwardly until the frictional engagement of the belt 115 with the pulley 114 is again sufficient to cause the actuation of the feed rollers 108. Thus the free end of the frame 109 is slightly raised and lowered during the feeding of the fabric. 70 75 80

Backward motion of the take-up rollers is prevented by a pawl 117 pivoted to the shaft 110 and engaging the gear wheel 111 in a manner to permit forward motion thereof and prevent backward motion thereof. Thus it will be seen that after each time the pawl 82 has been rendered inoperative, by the arm 90 engaging the latch arm 94, the pawl 82 may be rendered operative or returned into engagement with the ratchet wheel 80 at a predetermined period controlled by a projection 106 of the chain 102 engaging the dog 101 at a predetermined period during the operation of the machine. 90 95 100

From the foregoing description it will be seen that during the operation of the machine the pawl 83 remains constantly in engagement with the ratchet wheel 81 while the pawl 82 is moved into and out of operative engagement with the ratchet wheel 80 at predetermined intervals under the control of the pins 92 and the projections 106 of the pattern chain 102.

By this construction I am enabled to greatly vary the designs of the product of 105 the machine by not only changing the relation of the blocks 78 and 79 to each other upon the drums 69 and 70, but also by actuating the drum 70 only at certain predetermined intervals which changes the timing of the movement of the blocks 78 carried by the drum 69 with relation to the movement of the blocks carried by the drum 70. 110 115

I claim:—

1. In a knitting machine, the combination of the needles, their support, the cam cylinder, rotating means for the cam cylinder, means carried by the cam cylinder to actuate the needles to produce stitches, two independently rotatable members, means for rotating said members independently of each other during successive rotations of the cam cylinder, a thread-feeding part carried by the cam cylinder, a needle operating part, 120 and means controlled by each of said members for moving said needle operating part into and out of operative position.

2. In a knitting machine, the combination of the needles, their support, the cam cyl- 125 130

- inder; rotating means for the cam cylinder, means carried by the cam cylinder to actuate the needles to produce stitches, a pattern-controlling, needle-operating cam, two independently rotatable drums, means for rotating said drums independently of each other during successive rotations of the cam cylinder, adjustable patterning parts carried by each of said drums, and means controlled by the patterning part of each of said drums for operating the needle-operating cam.
3. In a knitting machine, the combination of the needles, their support, the cam cylinder, rotating means for the cam cylinder, means carried by the cam cylinder to actuate the needles to produce stitches, a thread feeding part carried by the cam cylinder, a needle operating part, two independently rotatable members, means controlled by each of said members for moving said needle operating part into and out of operative position, and means for rotating said members independently of each other, the last named means including a ratchet wheel connected to one of said members and a pawl coacting with said ratchet wheel.
4. In a knitting machine, the combination of the needles, their support, the cam cylinder, rotating means for the cam cylinder, means carried by the cam cylinder to actuate the needles to produce stitches, a thread feeding part carried by the cam cylinder, a needle operating part, two independently rotatable members, means controlled by each of said members for moving said needle operating part into and out of operative position, and means for rotating said members independently of each other, the last named means including a ratchet wheel connected to one of said members, a ratchet wheel connected to the other of said members, a pawl coacting with one of said ratchet wheels, a pawl coacting with the other of said ratchet wheels, and a part actuating both pawls.
5. In a knitting machine, the combination of the needles, their support, the cam cylinder, rotating means for the cam cylinder, means carried by the cam cylinder to actuate the needles to produce stitches, a thread feeding part carried by the cam cylinder, a needle operating part, two independently rotatable members, means controlled by each of said members for moving said needle operating part into and out of operative position, and means for rotating said members independently of each other, the last named means including a ratchet wheel connected to one of said members, a pawl coacting with one of said ratchet wheels, a pawl coacting with the other of said ratchet wheels, and a part moving said pawl out of engagement with the ratchet wheel at predetermined intervals.
6. In a knitting machine, the combination of the needles, their support, the cam cylinder, rotating means for the cam cylinder, means carried by the cam cylinder to actuate the needles to produce stitches, a thread feeding part carried by the cam cylinder, a needle operating part, two independently rotatable members, means controlled by each of said members for moving said needle operating part into and out of operative position, and means for rotating said members independently of each other, the last named means including a ratchet wheel connected to one of said members, a ratchet wheel connected to the other of said members, a pawl coacting with one of said ratchet wheels, a pawl coacting with the other of said ratchet wheels, a part actuating both pawls, and a part moving one of said pawls out of engagement with its ratchet wheel at predetermined intervals.

In testimony whereof I affix my signature in the presence of two witnesses.

EDGAR C. CHANDLER.
